UNITED STATES PATENT OFFICE

HARRY M. SWINDLER, OF DAYTON, OHIO, ASSIGNOR TO THE JAMES LEFFEL & COMPANY, OF SPRINGFIELD, OHIO, A CORPORATION OF OHIO

STOKER

Application filed February 7, 1930. Serial No. 426,480.

My invention relates to stokers.

It is an especial object of my invention to provide a hopper construction which is completely detachable and also slidable with respect to the stoker mechanism in order to permit of the inspection of the stoker ram, to permit the free opening of the doors of the stoker and to permit of the removal of refuse products from the furnace above the stoker through the doors with respect to the hopper.

It is a further object to provide a combination between the hopper, the ram and the retort whereby the fuel will be moved by the ram at each stroke without the arching and bridging of the fuel which renders the action of the ram substantially useless in delivering the fuel.

It is an object of this invention to provide mechanism that is especially adaptable to the limited area of the fire box of a Scotch marine boiler and to provide means of cleaning and having access to the interior of such a fire box without dismantling the stoker or its fuel delivery mechanism in order to withdraw refuse from the outside top portions of the tuyères where it has been forced in the course of the combustion of the fuel.

Referring to the drawings:

Figure 1 is a perspective of the ram end of the furnace;

Figure 2 is a top plan view thereof;

Figure 3 is a section on the line 3—3 of Figure 2;

Figure 4 is a section on the line 4—4 of Figure 3 showing the method of delivering and arranging fuel with respect to the ram to prevent the bridging of the fuel.

Referring to the drawings in detail, it will be understood that one of my primary objects is to provide my construction in connection with a Scotch marine boiler in which the fire box is circular, of very limited diameter and completely surrounded by water.

As set forth, illustrated and claimed in my copending application Serial No. 425,207, I have provided a stoker for insertion within the circular fire box of a Scotch marine boiler which has a retort having a bottom formed by the sliding pusher 1 which reciprocates upon the bottom ledges 2 and 3 of the retort

formed on the side walls 4 and 5. The legs 6 of the retort rest on the inside of the fire box 7 which is spaced from the outside boiler wall 8. The pusher 1 is connected to a ram 9 by the bolts 10. A cover plate 11 rests upon the top of the retort and is sloped inwardly and upwardly as at 12 to facilitate the delivery of the fuel by the pusher and ram. The outer end of the retort likewise has a cover plate 13 formed as a sliding support for the hopper 14 and its base casting 15 that is provided with the hand holds 16. The cover 13 is provided with an opening 14a which coincides with the bottom opening 17 of the hopper for delivery of fuel over the ram 9 and into the spaces 18 between the side walls of the retort and of the ram to prevent the bridging of the coal or other fuel over the ram.

By allowing the fuel to drop down in the spaces 18 the ram will move the coal into the retort at points within the fire box at each stroke whereas if the fuel is permitted to arch over the ram, fuel cannot drop down from the hopper 14 through the opening 17 and opening 14a and cannot be pushed into the fire box.

The cover 13 is provided with spaced shoulders 19 which engage the sides of the hopper support 15 to guide it fore and aft over the ram. The ram itself is driven through the pitman 20 from the crank 21 suitably operated through the gear box and its gearing generally designated 22, which gearing is operated by the motor 23. The gearing of this gear box and its associated mechanism is covered in my copending application Serial No. 425,208.

When it is desired to clean out the accumulation of clinker and ash on the tuyères 24 within the fire box, the hopper 14 can be drawn back to its rearmost position or completely removed from the plate 13 permitting the swinging of the quadrant-shaped doors 25 and 26 outwardly on their pivot pin 27 and the complete detachment of such doors if desired. The refuse is drawn out of the fire box on to the plates 28 and discharged laterally off of the inclined portions 29 on to the floor about the boiler and stoker.

The quadrant-shaped doors 25 and 26 which engage the semi-circular closure ring 30 fitted on the face of the boiler can be completely removed by reason of the following construction. The pivot pin 27 is held at its top in a bracket 31 by a cross pin 32. It is seated at the bottom in a socket 33 in the plate 13. The doors each carry hinge straps 34 and 35 mounted upon the pin 27. Hence, the removal of the hinge pin 27 permits the complete removal of the doors and full access to the interior of the fire box. In the Scotch marine boiler, this fire box is of very limited character and every inch of space must be availed of in order to introduce the stoker mechanism and still have room for complete access to the surface above the stoker for cleaning purposes.

The doors themselves are held in position, when closed, by the following mechanism. Right angular latch members comprising a handle 36 pivoted on the door at 37 and having a latch nose 38 which is limited in its movement by the stop 39 on the door. The door is held closed by a pivoted locking lever 40 pivoted at 41 on the lower face plate 42 closing the lower half of the front of the fire box. This lever engages its outer end with the stop 43 which limits its rotation downwardly on the outer end by reason of the weight 44.

The inner end is provided with a cam-shaped nose 45 that is engaged by the correspondingly cam-shaped nose 38 so that the lifting of the handle 36 depresses the nose 45 that locks the door shut and permits the door to be opened by swinging on its hinge pin 27.

It is thus possible by this construction to both remove the doors and the hopper or to withdraw the hopper and swing the doors open depending upon the extent of the access to the interior of the fire box above the retort and tuyères which may be desired.

It will be understood that I desire to comprehend within my invention such modifications as may be necessary to adapt it to varying conditions and uses.

Having thus fully described my invention, what I claim as new and desire to secure by Letters Patent, is:—

1. In combination, a boiler having a fire box, a retort mounted in said fire box in the lower half thereof, doors closing the upper half of the fire box, a fuel hopper mounted on said retort adjacent said doors, and means to slidably support said hopper with respect to the retort and doors to permit its withdrawal into an inoperative position and the opening of the doors.

2. In combination, a boiler having a fire box, a retort mounted in said fire box in the lower half thereof, doors closing the upper half of the fire box, a fuel hopper mounted on said retort adjacent said doors, means to slidably support said hopper with respect to

the retort and doors to permit its withdrawal into an inoperative position and the opening of the doors, and means supporting said doors adapted to permit their detachment without disturbing said hopper.

3. In combination, a boiler, centrally hinged doors closing the upper half of the fire box thereof, a stoker in the lower half of the fire box below the doors, a hopper slidably mounted on the exterior portion of said stoker adjacent the doors and central pivot means for said doors adjacent said hopper whereby said doors may be swung outwardly when the hopper is withdrawn from adjacent the doors.

4. In combination, a boiler, centrally hinged doors closing the upper half of the fire box thereof, a stoker in the lower half of the fire box below the doors, a hopper mounted on the exterior portion of said stoker adjacent the doors and central pivot means for said doors adjacent said hopper whereby said doors may be swung outwardly when the hopper is withdrawn from adjacent the doors and means for slidably mounting said hopper on said stoker to permit its withdrawal from a point adjacent said doors without detachment from the stoker.

5. In combination, a retort having an opening, a reciprocating ram therein reciprocating beneath said opening for delivering fuel into the retort, a slidable hopper mounted on said retort having a bottom opening adapted to coincide with the first mentioned opening.

6. In combination, a retort having an opening, a reciprocating ram therein reciprocating beneath said opening for delivering fuel into the retort, a slidable hopper mounted on said retort having a bottom opening adapted to coincide with the first mentioned opening, and means on said retort for guiding said hopper in its reciprocation.

7. In combination, a retort, having an opening, a reciprocating ram therein reciprocating beneath said opening for delivering fuel into the retort, a slidable hopper mounted on said retort having a bottom opening adapted to coincide with the first mentioned opening, and means on said retort for guiding said hopper in its reciprocation, said hopper comprising a hopper body and a sliding base.

8. In combination, a retort, a reciprocating ram therein reciprocating beneath an opening for delivering fuel into the retort, a slidable hopper mounted on said retort having a bottom opening adapted to coincide with the first mentioned opening, and means on said retort for guiding said hopper in its reciprocation, said hopper comprising a hopper body and a sliding base, said base having rearwardly disposed hand hold means for effecting its reciprocation.

9. In combination, a retort, a ram therein, said retort having a fuel delivery opening

over the ram into the retort and enlarged chambers communicating with said opening within the retort on either side of the ram for permitting the delivery of fuel to the sides of the ram as well as on top thereof within the retort whereby bridging of fuel is prevented, and a slideable hopper mounted on said retort for delivering fuel to the fuel delivery opening in the retort and said enlarged chambers.

10. In combination in a boiler of a fire box, a stoker mounted therein extending out of the fire box, hinged doors for closing the upper half of the fire box, a ram for delivering fuel, a retort for receiving fuel and guiding said ram, a slideable hopper for delivering fuel to said retort and ram adjacent said doors, and a refuse plate for receiving

refuse from said fire box and discharging it laterally to either side of said hopper and ram.

11. In combination in a boiler of a fire box, a stoker mounted therein extending out of the fire box, hinged doors for closing the upper half of the fire box, a ram for delivering fuel, a retort for receiving fuel and guiding said ram, a slideable hopper for delivering fuel to said retort and ram adjacent said doors, a refuse plate for receiving refuse from said fire box and discharging it laterally to either side of said hopper and ram, and means for completely detaching said doors from the fire box without disturbing said hopper and refuse plate.

In testimony whereof, I affix my signature.
HARRY M. SWINDLER.
